UNITED STATES PATENT OFFICE.

ARTHUR HABIG, OF MONTREAL, QUEBEC, CANADA.

SMOKE-CONSUMER.

1,278,639.

Specification of Letters Patent. Patented Sept. 10, 1918.

Application filed October 26, 1915. Serial No. 58,007.

To all whom it may concern:

Be it known that I, ARTHUR HABIG, a subject of the King of Great Britain, and resident of 905 De Montigny St. East, in 5 the city of Montreal, Province of Quebec, in the Dominion of Canada, engineer, have invented certain new and useful Improvements in Smoke-Consumers; and I do hereby declare that the following is a full, clear, 10 and exact description of the same.

The invention relates to improvements in smoke consumers as described in the present specification and shown in the accompanying drawings that form part of the same.

15 The invention consists essentially of the novel construction and arrangement of parts, whereby the unconsumed gases are drawn from the flue into the firebox through a chamber in the door.

20 The objects of the invention are to economize in the consumption of fuel, to eliminate the smoke nuisance particularly in great cities and generally to provide a simple economical and serviceable smoke consumer.

25 In the drawings, Figure 1 is a vertical sectional view of the furnace with the fire box door closed.

Fig. 2 is a front elevation of the furnace. 30 Fig. 3 is a horizontal sectional view through the door.

Fig. 4 is a vertical section of the door and adjoining wall.

Like numerals of reference indicate corresponding parts in each figure.

Referring to the drawings, it will be seen that in the furnace structure, there are twin furnaces, in each of which the door 1 is constructed with a pipe slot 2 in the upper 35 side thereof, immediately beneath which a box 3 is supported fitting around the edges of said slot and open at the end, said box being in the center of the inside of the door, having a central outlet hole 4 and secured 40 to the door by the back plate 5, the latter being bolted to said door.

The fire box of each furnace is fed 45 through a door opening 7 closed by the door 1 and emits smoke or unconsumed gases into the flue 8. These gases are drawn into the 50 return pipe 9 which terminates at the rear end in the bell mouth 10 and branches near

the front of the structure into two pipes 9¹ rectangular in cross section extending down the front wall of the furnace on their narrow sides and twisted above the line of the door openings and projecting on their flat broad sides to said door openings. A partial vacuum is created in the pipe 9 by the steam jet 11 spouting in the direction of the 55 return flow of gases and situated several feet from the flue 8. The onflow of the return gases is further assured by the steam jets at ends of the pipes 12 which spout into the fire boxes just above the door openings 60 and draw the gases inwardly from the boxes 3, which at their upper ends close over the delivery ends of the pipes 9¹. The steam also materially aids in promoting the combustion of the fuel in each fire box as well 65 as the unconsumed gases aforesaid and therefore these jets of steam serve two purposes, that is to say two jets of steam spouting into the fire boxes spray over the fuel and add combustible gases to aid the said 70 fuel to a state of incandescence as well as leaving behind the spoutings a partial 75 vacuum, for drawing the smoke or unconsumed gases emitted from the outlet hole in said door boxes. It has been explained 80 how the smoke is first drawn from the flue and it will now be seen that its flow is carried on by an entraining action directly into 85 a fire box and this is particularly facilitated by the chamber secured on the inside of each door which has its outlet just below each pipe 12.

It must be understood that many changes may be made in the construction so long as such differences come within the scope of 90 the claim for novelty following.

What I claim is:—

In a smoke consumer, the combination 95 with the furnace structure including a pair of boilers and fire boxes and flue, of a pipe extending forwardly from the flue between the boilers and terminating in said flue in a flaring end in the path of the unconsumed gases and at its forward end spreading into two distinct pipes, the latter being secured on the front wall of the furnace in the center thereof and of comparatively flat formation and at points higher than the fire box doors twisted and laid flat on the 100

furnace wall and extending laterally and downwardly to the fire box doors, doors to said fire boxes, an inner plate spaced apart from the front wall of each door, each of 5 said plates having a central opening, and steam jets situated in the return path of the unconsumed gases.

Signed at Montreal, Canada, this 14th day of June, 1915.

ARTHUR HABIG.
